UNITED STATES PATENT OFFICE.

JACOB SALATHE AND CHARLES SALATHE, OF NEW YORK, N. Y.

TAKE-UP MECHANISM FOR NARROW-WARE LOOMS.

SPECIFICATION forming part of Letters Patent No. 651,614, dated June 12, 1900.

Application filed October 9, 1899. Serial No. 733,017. (No model.)

To all whom it may concern:

Be it known that we, JACOB SALATHE and CHARLES SALATHE, citizens of the United States, residing in New York, (College Point,) 5 county of Queens, and State of New York, have invented certain new and useful Improvements in Take-Up Mechanism for Narrow-Ware Looms; and we do hereby declare the following to be a full, clear, and exact description of the invention, such as will enable others skilled in the art to which it appertains to make and use the same, reference being had to the accompanying drawings, and to letters of reference marked thereon, which form a 10 part of this specification.

This invention relates to take-ups for looms, especially for narrow-ware looms; and its object is to provide a take-up of simple, strong, and durable construction, reliable and 15 efficient in operation and readily attachable to looms of various makes and construction.

The invention consists in the improved take-up and in the combination and arrangement of the various parts thereof, substantially as will be hereinafter more fully described, and finally embodied in the clauses of the claim.

Referring to the accompanying drawings, in which like letters of reference indicate 30 corresponding parts in each of the several views, Figure 1 is a view in side elevation of a loom provided with our improved take-up, only those portions of the loom being shown which are necessary to fully illustrate 35 the nature of our invention. Fig. 2 is a rear elevation of a portion of Fig. 1, with certain parts broken away and others removed; and Fig. 3 is an enlarged detail view of the receiving-bobbins and their operating mechanism.

In said drawings, *a* represents the loom-frame; *b*, the batten, supported by lay-swords *c* in the usual manner, and *e* the main driving-shaft, which by suitable gear mechanism 40 (not shown in the drawings) transmits motion to the take-up roller *f*.

On the rear portion of the frame *a* are arranged the delivery-bobbins *d*, from which the warp-threads *g* pass over suitable pulleys 45 or sheaves *h* under a rod *i*, preferably of glass, which latter is supported in brackets

j, mounted on the loom-frame in the usual manner.

On the front beam *m* of the loom is secured a glass rod *n*, parallel with the rod *i*, while another glass rod *o* is arranged below and preferably in rear of the bracket *j*. On the rear of the loom and below the delivery-bobbins *d* are secured two parallel bars *p* and *p'*, in which are mounted a series of spindles *q* and *q'*, adapted to receive the receiving-bobbins *r* and *r'*. Between the cross-bars *p* and *p'* and above the same is revolubly mounted a shaft *s* in frictional contact with the lower heads or flanges of the receiving-bobbins *r* and *r'*. The shaft *s* is adapted to rotate the series of bobbins, and therefore in order that the shaft may properly transmit its motion to said bobbins the spindles *q* and *q'* are inclined more or less out of the perpendicular relatively to said shaft.

On the shaft *s* is mounted a sprocket-wheel *s'*, receiving its motion through a sprocket-chain *s''* from a smaller sprocket-wheel *s'''*, which latter is mounted on the main driving-shaft *e*.

On the shaft of the take-up roller *f* is secured a wheel or pulley *f'*, transmitting its motion through an endless belt *f''* to a wheel or pulley *f'''*, which latter is securely mounted on a shaft *f''''*, suitably supported in the loom-frame *a*. On the last-mentioned shaft *f''''* is also arranged a smaller grooved pulley *f'''''*, connected by an endless belt *f''''''* to a larger grooved pulley *f'''''''*, which latter is mounted on the shaft *u*, parallel with the shaft *f''''* and also arranged in the loom-frame *a*.

Secured on the shaft *u* is a cam *v* in alignment with and adapted to operate a shoe *v'*, carried by the rear portion of a treadle-lever *v''*, the front portion of which is suitably fulcrumed, as at *v''*, to a bracket *v'''*, arranged on the floor, or, if preferred, said bracket could be secured to and depend from the loom-frame, as will be manifest. The rear portion of the treadle-lever *v''* is connected by a rod *w* to a link or lever *w'*, one end of which is revolubly mounted on a shaft *w''*, while its free end is connected to the lower end of a rod or wire *w'''*. To the upper end of said rod or wire *w'''* is secured a rope *x*, passing over one of the sheaves or pulleys *h* and having its

other end secured to a depending rod x' , the lower hooked portion x^3 of which forms a bearing for the traverse-rod x^3 , which latter is parallel to the shaft s and is in close proximity to the receiving-bobbins r . Said traverse-rod x^3 is guided in its up-and-downward movement by means of bars or rods x^4 , adapted to reciprocate in brackets p^2 , as clearly shown in Fig. 3.

10 It may be stated that a weight x^5 may be arranged on the lower end of the reciprocating bars or rods x^4 , if found necessary.

15 In the foregoing we have described the traverse-rod and its operating mechanism, and it must be remarked that a similar mechanism is arranged on the opposite side of the loom and, if desired, can also be arranged at certain intermediate portions thereof.

20 On a cross-beam y in the front portion of the loom are secured a series of brackets y' , forming the bearings for a series of guide pulleys or wheels y^2 , which latter are in close proximity to and preferably in frictional contact with the take-up roller f for a purpose 25 hereinafter described.

25 The finished fabric passes over the rod n , under and over the take-up roller f , over its respective guide-wheel y^2 , under the rod o , and over the traverse-rod x^3 onto the receiving-bobbin r or r' .

30 In operation the shaft s being rotated in turn rotates the receiving-bobbins r and r' , on which latter the finished fabric is being wound. Simultaneously the cam v engages the shoe v' , and thus depresses the treadle-lever v^2 . The latter, through the rod or wire w^3 (and intermediate connections) and through the rope x and depending rods x' , raises the traverse-bar x^3 gradually to its uppermost 35 position, which latter rod thereafter by its own weight or assisted by the weight x^5 gradually descends when the cam v is returning to its normal position—that is to say, to the position illustrated in Fig. 1. By this arrangement the fabric is wound upon the receiving-bobbins in uniform layers, and it will be manifest that the length of travel of the traverse-rod x^3 can easily be adjusted or regulated by securing the link w in one or the other 40 of the openings in the arm or lever w' .

45 Heretofore the finished fabric after passing under and over (or vice versa) the regular take-up roller f was allowed to drop into a box or receptacle placed underneath said take-up roller. The material was afterward removed from said box and wound on the receiving-bobbins. With our improved device the last-mentioned operations are automatically effected, and it undoubtedly simplifies 50 the operation and lessens the steps necessary for the same.

55 We do not intend to limit ourselves to the precise construction shown and described, as various alterations can be made without changing the scope of our invention; but

60 What we claim as new, and desire to secure by Letters Patent, is—

1. In a take-up for looms, the combination with the frame and the main driving-shaft, of a shaft journaled parallel with said main driving-shaft, series of spindles arranged in close proximity to the parallel shaft and disposed out of the perpendicular relatively thereto, receiving-bobbins revolvably mounted on said spindles and in frictional contact with said shaft, a reciprocating traverse-rod parallel with said shaft and in close proximity to the bobbins, means for reciprocating said traverse-rod, and means for transmitting motion from the main driving-shaft to the other shaft, substantially as and for the purposes set forth. 70 75

2. In a take-up for looms, the combination with the frame and the main driving-shaft, of a take-up roller operated from said main driving-shaft, a shaft journaled parallel with the main driving-shaft and operated therefrom, series of spindles arranged in close proximity to the parallel shaft and disposed out of the perpendicular relatively thereto, receiving-bobbins revolvably mounted on said spindles and in frictional contact with the parallel shaft, a suitably-guided traverse-bar in close proximity to the bobbins, an auxiliary shaft revolvably mounted in the frame, means for transmitting the motion from the take-up roller to said auxiliary shaft, a cam mounted on the last-mentioned shaft, a suitably-fulcrumed treadle-lever in alinement with and adapted to be operated by said cam, and means for transmitting motion from said treadle-lever to the traverse-bar, substantially as and for the purposes described. 80 85 90

3. In a take-up for looms, the combination with the frame and the main driving-shaft, of a take-up roller operated from said main driving-shaft, a shaft journaled parallel with the main driving-shaft and operated therefrom, series of spindles arranged in close proximity to the parallel shaft and disposed out of the perpendicular relatively thereto, receiving-bobbins revolvably mounted on said spindles and in frictional contact with the parallel shaft, a suitably-guided traverse-bar in close proximity to the bobbins, an auxiliary shaft revolvably mounted in the frame, means for transmitting the motion from the take-up roller to said auxiliary shaft, a cam mounted on the last-mentioned shaft, a suitably-fulcrumed treadle-lever in alinement with and adapted to be operated by said cam, another lever adjustably connected with said treadle-lever, and means for transmitting motion from said fulcrumed lever to the traverse-bar, substantially as and for the purposes described. 100 105 110 115 120 125

4. In a loom the combination with the frame, the main driving-shaft, the take-up roller, and with the delivery-bobbins, of a series of parallel rods intermediately arranged between the take-up roller and the delivery-bobbins, a shaft journaled parallel with the main driving-shaft and operated therefrom, series of spindles arranged in close proximity 130 135

to said shaft and disposed out of the perpendicular relatively thereto, series of receiving bobbins revolubly mounted on said spindles and in frictional contact with the parallel 5 shaft, a suitably-guided traverse-bar in close proximity to the receiving-bobbins and means operated from the take-up roller for reciprocating said traverse-bar, substantially as and for the purposes described.

In testimony that we claim the foregoing to we have hereunto set our hands this 5th day of October, 1899.

JACOB SALATHE.
CHARLES SALATHE.
